UNITED STATES PATENT OFFICE.

PHILLIP J. DELL, JR., OF WAYCROSS, GEORGIA.

SWITCH-POINT TIE-BAR.

1,249,912.

Specification of Letters Patent. Patented Dec. 11, 1917.

Application filed September 16, 1916. Serial No. 120,537.

To all whom it may concern:

Be it known that I, PHILLIP J. DELL, Jr., a citizen of the United States, residing at Waycross, in the county of Ware and State of Georgia, have invented certain new and useful Improvements in Switch-Point Tie-Bars; and I do hereby declare the following to be a full, clear, and exact description of the invention, such as will enable others skilled in the art to which it appertains to make and use the same.

The object of this invention is the provision of a novel type of sectional tie or connecting bar for the points of a railway switch, which can be adjusted in a convenient manner to effect the proper gage of the switch points; also the provision of novel retaining means for effectively holding the sections in adjusted position.

Other objects will appear and be better understood from that embodiment of my invention of which the following is a specification, reference being had to the accompanying drawing forming a part thereof, in which:

Figure 1 is a side view of the connecting bar, showing the same associated with the switch points.

Fig. 2 is a detail perspective view of a switch point operating bar, showing the manner of connecting the tie bar sections thereto.

Fig. 3 is a fragmentary top plan view of a railway switch, showing the tie connecting bar connected to the switch points of the switch,

Fig. 4 is a perspective view of one of the sections of the tie connecting bar,

Fig. 5 is a sectional view, taken on the line 40 5—5 of Fig. 1.

Referring to the drawing in detail, the letter A designates the main rails of a track, and B the movable switch points. The switch point operating bar 1 extends below the rail A, and is provided at a point intermediate its ends and between the rails A with a U-shaped bracket 2, and is also provided at points spaced from the opposite sides of the U-shaped bracket 2 with apertured lugs 3, which are carried by circular plates 4 which rest on the upper surface of the operating bar 1 and have threaded stems 5 depending therefrom and received by openings in the operating bar 1, as shown more particularly in Fig. 5 of the drawing, the said stem having the lower end thereof pro-

vided with a nut 6, which is adjustable against the under face of the bar 1, and a jam nut 7 is turned on the lower end of the stem and adjustable against the lower face 60 of the nut 6, for preventing the retrograde rotation of the nut 6. The connecting or tie bar for the switch point is shown as consisting of a pair of sections 8, which extend through the apertured lugs 3 and through 65 openings in the sides of the U-shaped bracket 2, the inner ends of the sections 8 being arranged in spaced and opposed relation between the sides of the U-shaped bracket 2. The outer ends of the sections 8 are terminally bent upwardly, as shown at 9, and connected to the plates 10, which are adapted to be secured to the inner faces of the switch point B by means of fastening elements, which extend through the switch points and 70 through apertures in the plates 10. The inner ends of the sections 8 are threaded, and nuts 11 and 12 are adjustably mounted on the threaded ends of the sections 8, and are located on opposite faces of the sides of the 75 U-shaped bracket 2, as shown in Fig. 1 of the drawing. When it is desired to adjust the switch point, the nuts 11 and 12 are rotated so as to cause them to travel away from the sides of the U-shaped bracket 2. The 80 sections 8 are then moved in the proper direction to effect the proper gage of the switch points, after which the nuts 11 and 12 are adjusted against the sides of the U-shaped bracket 2 so as to hold the rods 8 in 85 adjusted position. The rods 8 have those portions which extend through the apertured lugs 3 provided with depressions 13, and adjustable through the lugs 3 are set screws 14, which are adapted to have their 90 inner ends interchangeably received by the depressions 13 so as to further assist in holding the sections 8 against movement when in adjusted position. The lugs 3 form supports to the rods 8 at points intermediate 95 their ends, and which will hold the rods against accidental movement if the nuts 11 and 12 become loose. Jam nuts 15 are mounted on the set screws 14 and are adjustable against the lugs 3 and serve to prevent 100 accidental retrograde rotation of the set screws 14.

It is evident that various changes might be resorted to in the construction, form and arrangement of the several parts without departing from the spirit and scope of my invention; hence I do not wish to limit myself 110

strictly to the structure herein described and claimed.

Having thus described my invention what I claim as new, is:

5 The combination with a switch operating bar, of a pair of apertured lugs carried by the bar, a switch point tie bar adjustable through the lugs and formed of sections, each of the sections having a plurality of
10 depressions therein, and means operable

through the lugs and adapted to be interchangeably received by the depressions in the sections of the tie bar for holding the sections against movement.

In testimony whereof I affix my signature 15 in presence of two witnesses.

PHILLIP J. DELL, JR.

Witnesses:

E. N. DZIER,
ADRON F. ELLISTON.
